UNITED STATES PATENT OFFICE.

ART HADLEY, OF PROVIDENCE, RHODE ISLAND.

BRACELET-LINK.

1,177,181.

Specification of Letters Patent. Patented Mar. 28, 1916.

Application filed November 5, 1914, Serial No. 870,398. Renewed January 4, 1916. Serial No. 70,309.

To all whom it may concern:

Be it known that I, ART HADLEY, a subject of the King of Great Britain, residing at Providence, in the county of Providence and State of Rhode Island, have invented a new and useful Improvement in Bracelet-Links, of which the following is a specification.

This invention relates to certain new and useful improvements in bracelet links, and pertains more particularly to a link employed in an expandible bracelet of the type disclosed in Patent No. 1115336, issued October 27, 1914, to C. L. Rhodes.

15 The primary object of the invention is to provide a link for bracelets in which same can be made from stock plated on four sides without exposing the raw edge.

Still further, the invention aims to provide a link which can be easily and quickly made and which is possessed of maximum strength.

Still further and other objects of the invention will be hereinafter referred to and manifested in the course of the following specification.

In the drawings—Figure 1 is a perspective view of the invention. Fig. 2 is an end elevation. Fig. 3 is a fragmentary side elevation. Fig. 4 is a plan view of the blank from which the link is formed, and Fig. 5 is a similar view of the blank from which clasp or coupling is formed.

In proceeding in accordance with the present invention a blank 1 is employed which is of strip-like form as shown in Fig. 4. The ends of the blank are of T-shape, that is to say, side extensions 2 are produced at the ends of the blank, preferably by swaging. The blank is first bent into the somewhat elliptical shape shown in Fig. 1, the extreme edges of the ends of the blank abutting or meeting on a line 3, as shown in Figs. 1 and 2, and 3.

45 The clasp or coupling consists of a blank

4 of H-shape which is placed on the interior of the link and has its four arms 5 projecting above and below the top and bottom sides of the link, and in engagement with the end extensions 2, after which the arms 50 5 are bent toward one another so as to embrace or surround the extensions 2, as depicted in the drawings. Since the arms 5 engage the top and bottom sides of the links as clearly shown in Figs. 1 and 2, it will 55 be apparent that the coupling is prevented from having lateral movement relative to the link. It will further be apparent that the coupling acts to brace the jointed end of the link, and also provides a means whereby the link is formed without the use of solder.

The link is used for the same purpose as the link 2 shown in Figs. 1 and 2 of the aforementioned patent.

Having thus described my invention, I claim as new and desire to secure by Letters Patent;

1. In a bracelet link, a link body formed of a strip-like link having an extension on each side of each end thereof, the extremities of the ends of the blank being engaged with each other, and a coupling of H-shape engaged on the inner face of said end of the link and having the arms thereof bent over 75 the extensions and toward one another and disposed on the outer face of said end of the blank.

2. In a bracelet link, a link body having side extensions on its ends, the ends of the 80 link being engaged with each other, and a coupling which embraces the extensions.

In testimony whereof I have signed my name to this specification in the presence of two subscribing witnesses.

ART HADLEY.

Witnesses:

ADA E. HAGERTY,
J. A. MILLER.
